UNITED STATES PATENT OFFICE.

JAMES J. MADDEN, OF ABERDEEN, SOUTH DAKOTA.

DESIGN FOR A LENS FOR HEADLIGHTS.

52,848.

Specification for Design.

Patented Jan. 7, 1919.

Application filed August 28, 1917. Serial No. 188,690. Term of patent 7 years.

To all whom it may concern:

Be it known that I, JAMES J. MADDEN, a citizen of the United States of America, and resident of Aberdeen, in the county of Brown and State of South Dakota, have invented a new, original, and ornamental Design for a Lens for Headlights, of which the following is a specification, reference being had to the accompanying drawing, forming part thereof.

Figure 1 is a plan view of one side of the lens embodying my design;

Fig. 2 is a plan view of the opposite side thereof;

Fig. 3 is a sectional view on the line 3—3 of Fig. 1; and

Fig. 4 is a sectional view on the line 4—4 of Fig. 2.

I claim:

The ornamental design for a lens for headlights, as shown.

JAMES J. MADDEN.
